UNITED STATES PATENT OFFICE.

JOHN H. TARBELL, OF NEW YORK, N. Y., ASSIGNOR TO CHENEY BROTHERS, OF SOUTH MANCHESTER, CONNECTICUT.

DESIGN FOR A HANDKERCHIEF.

SPECIFICATION forming part of Design No. 22,334, dated April 11, 1893.

Application filed February 6, 1893. Serial No. 461,267. Term of patent 3½ years.

To all whom it may concern:

Be it known that I, JOHN H. TARBELL, a citizen of the United States, and a resident of the city and county of New York, State of New York, have invented and produced a new and original Design for a Handkerchief, of which the following is a specification, reference being had to the accompanying drawing, forming a part hereof.

10 The object of my invention is to provide a design that may be wrought into or printed or similarly displayed upon the surface of a fabric used as a handkerchief, and such design is produced in the colors and tints found 15 in the national colors of the various nations.

My design consists in a handkerchief having a center a and a border b as its main component parts; the center a having displayed in the corners the national flag of the United States, as shown in the accompanying drawing. Outside of this center is the border that is made up or composed of an arrangement of the flags of various nations depicted in the appropriate colors and displaying on them the national arms, or such designs and figures as form a part of such flags.

What I claim is—

The design for a handkerchief comprising a center with the national flag of the United States displayed in colors in the several corners and a border made up of the flags of various nations also made up in colors, as shown.

JOHN H. TARBELL.
